ARTICULATED DISH STAND OR SIMILAR ARTICLE

Robert B. Greer, Los Angeles, Calif.

Application June 16, 1955, Serial No. 36,536

Term of patent 3½ years

(Cl. D44—10)

Fig. 1.

Fig. 2.

Fig. 1 is a plan view of an articulated dish stand or similar article in flat position and showing my new design.

Fig. 2 is a side elevational view showing the stand in a converted position with the lower sides folded to a substantially vertical position and the upper sides folded to an angularly flaring position.

The dominant features of the design reside in the portions shown in full lines. The part of the stand not shown in detail is the same as the part that is shown.

I claim:

The ornamental design for an articulated dish stand or similar article, substantially as shown and described.
